United States Patent Office

Des. 213,446
Patented Mar. 4, 1969

213,446

OPTICAL INPUT UNIT

Edward J. Sabella, Raleigh, N.C., assignor to International Business Machines Corporation, Armonk, N.Y., a corporation of New York

Filed Apr. 15, 1968, Ser. No. 11,470

Term of patent 14 years

U.S. Cl. D26—5
Int. Cl. D16—08

FIG. 1

FIG. 2

FIG. 3

FIG. 4

FIG. 1 is a perspective view taken from the front and left side of an optical input unit embodying my new design;

FIG. 2 is a perspective view taken from the rear and right side thereof;

FIG. 3 is a top plan view thereof; and

FIG. 4 is a bottom view thereof.

The dominant features of my design reside in the portions shown in solid lines.

I claim:

The ornamental design for an optical input unit, as shown and described.
